UNITED STATES PATENT OFFICE.

BENJAMIN F. LIVENGOOD AND GEORGE W. LIVENGOOD, OF CENTERVILLE, IOWA.

GRAVE-MARKER.

SPECIFICATION forming part of Letters Patent No. 792,835, dated June 20, 1905.

Application filed February 10, 1905. Serial No. 245,153.

To all whom it may concern:

Be it known that we, BENJAMIN F. LIVENGOOD and GEORGE W. LIVENGOOD, citizens of the United States, residing at Centerville, in the county of Appanoose and State of Iowa, have invented certain new and useful Improvements in Grave-Markers, of which the following is a specification.

The object of this invention is to provide improvements in that class of markers commonly used in cemeteries for indicating grave locations. The usual construction of markers used for this purpose embodies a number of parts made of stone, glass, composition, or the like, and under the ordinary conditions of service freezing and consequent swelling of the ground and thawing and settling of the earth naturally causes separation of the parts of the marker, so that in a few years the same is practically dismantled.

The invention comprises a marker or monument which is composed of parts; but the said parts are so constructed that they will accommodate for the swelling and settling of the earth in such a manner that the parts are adapted to separate and allow for swelling of the earth, but will resume their original compact positions as when put up upon settling of the earth which surrounds them.

For a full description of the invention and the merits thereof and also to acquire a knowledge of the details of construction of the means for effecting the result reference is to be had to the following description and accompanying drawings.

While the invention may be adapted to different forms and conditions by changes in the structure and minor details without departing from the spirit or essential features thereof, still the preferred embodiment is shown in the accompanying drawings, in which—

Figure 1 is a perspective view of a grave-marker comprising the invention. Fig. 2 is a transverse sectional view bringing out more clearly the construction and arrangement of the several parts which compose the invention. Fig. 3 is a perspective view of one of the transverse foundation-pieces.

Corresponding and like parts are referred

to in the following description and indicated 50 in all the views of the drawings by the same reference characters.

In carrying out the invention it is to be understood that the various parts of the marker, as shown in the drawings and as generally described, may be of any ornamental configuration in order to conform with the whim and tastes of the purchaser, the general form of the markers being different in almost every instance.

The invention comprises the usual headstone 1 and footstone 2, if it is desired to use these parts, and the headstone is of course provided with suitable inscriptive data generally provided thereon and indicating the 65 dates of birth, decease, &c., of the person who is buried in the grave. The headstone and footstone, if used, are carried by the transverse foundation-pieces 3, which will be placed at the head and at the foot of the grave, said 70 foundation-pieces being of peculiar form in order to support longitudinal or side pieces 4, which are commonly disposed in spaced relation upon opposite sides of and extending the entire length of the burial-mound. The transverse foundation-pieces 3 may be of any suitable material—stone, metal, or the like—and extending upwardly from the said pieces 3 at a point approximately intermediate of the 75 ends thereof are vertical extensions 5. The 80 extensions 5 of each of the foundation-pieces 3 are designed to carry or directly support the headstone 1 and the footstone 2, and the preferred means for attaching the stones 1 and 2 and the members 5 consist of a mortise- 85 and-tenon joint therebetween, the tenons 6 projecting upwardly from the extensions 5, so as to be received in the mortises 7, provided in the members 1 and 2. It is designed to utilize any suitable means for connecting the 90 head and foot stones to the extensions 5 with- 95 in the contemplation of the invention, how- ever. The foundation-pieces 3 will ordinarily be entirely covered by the earth and not be- ing visible may therefore be of rough ma- terial, though necessarily very substantial. At the ends of the foundation-pieces 3 are formed upwardly-projecting inwardly-inclined sur-

faces 8, and the end portions of the side pieces 4 rest upon the foundation-pieces 3 at points between the inclined surfaces 8 and the extensions 5. The side pieces 4 of the marker 5 extend laterally at the ends, as shown at 9, and abut with opposite sides of the extensions 5 of the foundation-pieces. In order to positively position the side pieces 4 with relation to the foundation-pieces and obviate likelihood of longitudinal play or movement, the laterally-extending portions 9 of the side pieces which abut with the extensions 5 have interlocking connection with the extensions in such a manner as to accomplish the result 10 above premised. To afford the interlocking connection between the side pieces 4 and the extensions 5, opposite sides of the extensions 5 are provided with vertical tongues 10, the meeting or adjacent portions of the side pieces 20 4 having grooves or vertical recesses 11, wherein the tongues 10 are received when the side pieces are in position upon the foundation-pieces after the marker has been set up over the grave. The connection between the 25 side pieces and the extensions 5 subserve the general rigidity of the marker and increases the compactness of the arrangement in a manner readily apparent. The headstones and the footstones when in position upon the extensions 30 5 are designed to overlap the joint between said extensions of the side pieces 4 in such a manner as to effectively house the joint and hide the same, so that such will not detract from the general appearance of the 35 marker.

In the actual use of the invention the earth is of course received between the side pieces 4 of the marker when the latter has been placed over the grave, and in cold weather 40 when the earth freezes and swells the side pieces 4 will naturally be forced apart and caused to ride upwardly upon the inclined surfaces 8 of the foundation-pieces 3. Now when the earth settles after being thawed out in 45 warm weather the weight of the side pieces 4 will cause the same to gradually resume their original positions, said side pieces settling with the earth and sliding toward the extensions 5 in a manner which will be readily apparent.

The structure of the parts is such that no growth is likely to spread in crevices between the several pieces composing the marker and conduce to the gradual destruction thereof, 50 which is a common defect now existing in the markers at present in use.

Having thus described the invention, what is claimed as new is—

1. A grave-marker comprising foundation-pieces having upwardly-projecting inclined 60 surfaces, and side pieces resting upon the foundation-pieces and co-operating with the inclined surfaces aforesaid.

2. A grave-marker comprising transverse foundation-pieces provided near the ends 65 thereof with upwardly-projecting inwardly-inclined surfaces, extensions projecting from the foundation-pieces, and side pieces resting upon the foundation-pieces at a point between the extensions thereof and the inclined surfaces aforesaid.

3. A grave-marker comprising transverse foundation-pieces provided near the ends thereof with upwardly-projecting inwardly-inclined surfaces, extensions projecting from 75 the foundation-pieces, and side pieces resting upon the foundation-pieces at a point between the extensions thereof and the inclined surfaces aforesaid, the side pieces having interlocking connections with the extensions above 80 mentioned.

4. A grave-marker comprising transverse foundation-pieces provided near the ends thereof with upwardly-projecting inwardly-inclined surfaces, extensions projecting from 85 the foundation-pieces, and side pieces resting upon the foundation-pieces at a point between the extension thereof and the inclined surfaces aforesaid, the side pieces and extensions having a tongue-and-groove connection. 90

5. A grave-marker comprising transverse foundation-pieces provided at the ends thereof with upwardly-projecting inclined surfaces, extensions projected from the foundation-pieces at a point between the ends thereof, 95 said extensions being adapted to receive a head or foot stone, and side pieces having the ends thereof resting upon the foundation-pieces at points between the extensions and the inclined surfaces thereof, the side pieces 100 being in abutting relation with the extensions, the meeting portions of the side pieces and extensions having a tongue-and-groove connection.

In testimony whereof we affix our signatures in presence of two witnesses.
